US00D771759S

(12) **United States Design Patent** (10) **Patent No.:** **US D771,759 S**
(45) **Date of Patent:** **** Nov. 15, 2016**

(54) **EXERCISE BAND**

- (71) Applicant: **Franci Cohen**, Brooklyn, NY (US)
(72) Inventor: **Franci Cohen**, Brooklyn, NY (US)
(**) Term: **15 Years**
(21) Appl. No.: **29/542,988**
(22) Filed: **Oct. 20, 2015**

Related U.S. Application Data

- (63) Continuation-in-part of application No. 29/485,908, filed on Mar. 24, 2014, now Pat. No. Des. 741,419.
